UNITED STATES PATENT OFFICE.

ALBERT STEFFIN, OF NEW BEDFORD, MASSACHUSETTS, ASSIGNOR TO THE MOUNT WASIIINGTON GLASS COMPANY, OF SAME PLACE.

DESIGN FOR A CONDIMENT-HOLDER.

SPECIFICATION forming part of Design No. 22,781, dated September 12, 1893.

Application filed March 31, 1891. Serial No. 468,617. Term of patent 7 years.

To all whom it may concern:

Be it known that I, ALBERT STEFFIN, a citizen of the United States, residing at New Bedford, in the county of Bristol and State of Massachusetts, have invented and produced a new and original Design for a Condiment or other Holder, of which the following is a specification, reference being had to the accompanying drawing, showing my design.

10 The leading feature of my design is a cone-shaped receptacle having a base of contracted diameter.

15 A is the receptacle of a general cone-shape, the largest diameter being at a' . From a' upwardly to the apex receptacle A is of constantly decreasing diameter; and from a' to

its flattened base, it also constantly decreases in diameter. The apex B is perforated at b and forms the subject-matter of my pending application, Serial No. 468,619, filed March 31, 1893, and all rights to the same are expressly reserved. The body of receptacle A is shown as fluted vertically from the base toward apex B, the flutings being somewhat irregular and converging at a^2 . 25

What I claim is—

The design for a condiment or other holder herein shown and described.

ALBERT STEFFIN.
